UNITED STATES PATENT OFFICE.

EDWARD P. NOYES, OF WINCHESTER, MASSACHUSETTS, ASSIGNOR, BY MESNE ASSIGNMENTS, TO C. P. POWER COMPANY, OF NEWARK, NEW JERSEY, A CORPORATION OF NEW JERSEY.

VACUUM APPARATUS.

979,788.

Specification of Letters Patent. Patented Dec. 27, 1910.

Application filed November 29, 1907. Serial No. 404,214.

To all whom it may concern:

Be it known that I, EDWARD P. NOYES, a citizen of the United States, residing at Winchester, in the county of Middlesex and 5 State of Massachusetts, have invented certain new and useful Improvements in Vacuum Apparatus, of which the following is a specification.

This invention relates to means for controlling and for utilizing the mechanical pumping suction of an internal-combustion motor, such as an explosion motor. In connection with such a motor suitable means are preferably provided whereby the difference in fluid pressure created by the suction of the piston or equivalent element in supplying the motor with its own combustion fluid is applied to the performance of mechanical work other than that of mere 15 charge-formation. Thus I am enabled to enhance the usefulness of these motors by applying them directly to the production of vacuums for industrial purposes without the intervention of a separate vacuum pump 20 driven by the motor.

My present invention is especially concerned with the throttle-control of one or more supply passages to a motor of this type, and in carrying out the invention with 30 the common type of explosion motor, I prefer to extend its suction conduit or pipe, generally the air pipe, to the desired point of use anterior to the motor with respect to the direction of fluid flow in said pipe and 35 there equip said pipe with the necessary devices for mechanically applying the vacuum. These devices may be of any known or suitable type for utilizing the elastic fluid flow due to the vacuum, or for utilizing the difference in pressure between atmosphere and 40 the suction pressure created by the motor. Specifically, the vacuum-using apparatus may, as hereinafter shown, consist of means for gathering dust from external objects 45 such as the interiors of buildings, together with a suitable strainer for separating the dust from the motor air-current on which it is borne.

When the combustible-charge-forming device of the motor consists of a liquid-fuel 50 mixer or carbureter operated by the passage of the air-current, I have found it desirable to effect certain changes in the construction of said mixer whereby the pressure in its fuel-reservoir, instead of being atmospheric

pressure or some arbitrary derivative, is made to depend upon the vacuum impressed upon the mechanical work-performing device associated with the suction-pipe, whereby the fuel-supply is regulated more or less according to the work done by or through said device. This expedient however is not claimed in the present application.

Of the accompanying drawings, Figure 1 65 represents an elevation, partly in section, showing my invention in the form of an automobile whose propelling motor is equipped to furnish a vacuum for collecting dust from external objects. Fig. 2 represents a sectional view of the carbureter. Fig. 3 represents a sectional view of the automatic air-inlet valve. Fig. 4 represents a vertical section of one of the motor cylinders.

10 is the frame of the vehicle and 11 is the propelling motor, here shown as a two-cylinder motor with an air-suction pipe 12 leading through a carbureter 13 and continuing as a combustible-mixture pipe 14 80 branching to the respective cylinders. The four-stroke cycle and the two-stroke cycle are common types of explosion motors to both of which my invention applies, the difference as regards the application of the invention, lying in the fact that the suction-pipe leads into the combustion-cylinder in the case of a four-stroke motor, and into 85 a displacer-chamber, usually the crank-chamber, in the case of a two-stroke motor. I have shown an ordinary four-stroke cycle motor.

The suction-pipe 12 is shown as extended anteriorly for the purpose of applying the motor suction to extraneous objects and controlling the motor from a distance, and when the extraneous objects are dust-particles or surfaces requiring to be cleaned of dust, the inlet-end of the suction-pipe is furnished 95 with a dust-gathering tool 15 of any suitable pattern, and with a flexible section or hose 17 carrying said tool, so that the tool may be moved about. The flexible hose enables the tool 15 to reach places from which dust is to be gathered, and it also enables the motor to be controlled from a shifting locality. A valve 16 in said air-pipe near the suction instrument enables the air inlet to be shut off or regulated, and the motor itself may be throttled and regulated with 100 110

this valve. However, in applications other than dust-gathering, or wherever the object to be acted on has a permanently-fixed or determinate location with respect to the motor the flexible section of the suction-pipe may generally be dispensed with. The extent of this pipe will depend upon the proximity of the suction-using device, and the particular character of said device may be varied according to the kind of work to be performed.

A dust-strainer or separator of any suitable type is provided in the suction-pipe between the hose 17 and the carbureter 13. I have shown a strainer 21 composed of an outer casing and an inner porous removable bag 22 for retaining the dust and permitting a purified combustion-air current to go to the motor.

Modification of the usual carbureter arrangement in which the float chamber is open to atmospheric pressure is here effected by substantially sealing the float-chamber or reservoir 23 of the carbureter against the entrance of atmospheric air, and leading an air-pressure duct 24 to said chamber from a point in the suction pipe anterior to the fuel-mixing point. Hence when the air-supply becomes more or less rare because of a varying vacuum, the motive pressure on the surface of the fuel in chamber 23 varies conformably, and a tendency is established to automatically maintain fixed ratios of air and fuel in the combustible mixture.

At a suitable point anterior to the carbureter, the suction-pipe 12 is provided with a branch air-inlet 26, controllable at will, for use in starting the motor, in running the vehicle under its own power, etc., and there may be a two-way valve 25, with a suitable operating device, for putting either the inlet 26 or the pipe 12 into communication with the carbureter, that is, for directing the motor suction at will either to the inlets 15 and 28 on the one hand, or to the inlet 26 on the other hand. It will be seen that this valve is a switching valve, controlling two ports reciprocally by one motion. I do not however wholly confine myself to the use of a single valve for this directive function. The valve 25 is able to perform throttle regulation for inlet 26.

A second branch inlet 28 to the suction-pipe 12 is equipped with an automatic air-pressure-operated mechanism 27 including a valve 29, a piston 30, and a valve-closing

spring 31. On its lower side the piston has atmospheric pressure, and on its upper side the suction pipe pressure plus that of spring 31, so that the valve tends to open when a predetermined degree of vacuum is attained in pipe 12. Hence if the flow through the dust-tool 15 should be interrupted by the closing of valve 16 or kinking of the hose, the motor would not be deprived of combustion air. The device 27 may also be adjusted to correct the surging in motor speed which might otherwise be observed because of the elasticity of a large body of air in the suction-pipe. Such surging is observed principally at low speed under nearly-closed throttle. In order to make a relatively-high vacuum available at the nozzle 15, the spring of the relief-valve device 27 is of course usually set so as not to allow the valve 29 to open until the motor is well throttled down, in which case stalling of the motor is prevented. Up to that point the throttle valves 16 and 25 are able to control the motor performance. This device, while preferably used where a strong vacuum is desired, is not indispensable.

My invention is adapted to stationary as well as portable or vehicle-propelling motors, and may of course be varied in its constructional embodiment.

I claim,—

1. Vacuum apparatus comprising an automatic internal-combustion motor having means for mechanically pumping its combustion-air charge, an anteriorly-extended air-supply pipe for said motor having a movable portion carrying the air inlet, and a throttle valve in the movable portion of said pipe.

2. Vacuum apparatus comprising an automatic internal-combustion motor adapted to mechanically pump its combustion-air charge, an anteriorly-extended air-suction pipe having a plurality of suction inlets one of which is provided with means for applying the motor suction to the performance of external work, and throttle-valves for the respective inlets controllable at will.

In testimony whereof I have hereunto set my hand in the presence of two subscribing witnesses, the 26th day of November 1907.

EDWARD P. NOYES.
